UNITED STATES PATENT OFFICE

ERNEST H. WOLBER, OF CLIFTON, NEW JERSEY

TILE CUTTING MACHINE

Application filed January 19, 1931. Serial No. 509,647.

The main object of this invention is to provide a machine for cutting and fracturing tile or the like upon a predetermined line.

Another object of the invention is to provide a tile cutting machine for dividing tile or ceramics and utilizes a disk mounted on a spindle whose pressure on the tile may be augmented by the manipulation of a lever.

The above and other objects will become apparent in the description below in which characters of reference refer to like-named parts in the drawings.

Referring briefly to the drawings, Figure 1 is a top plan view of the assembled tile cutting machine.

Figure 2 is a side elevational view of Figure 1 showing the cover removed to illustrate the mechanism.

Figure 3 is a front elevational view of the spindle operating lever and pressure trigger.

Figure 4 is a sectional end elevational view taken on line 4-4 of Figure 2.

Referring in detail to the drawings the numeral 10 indicates a substantial rectangular platen which is dished out on its under side to provide a space in which bosses 11 and 12, spaced apart from each other, are provided. The bosses integral with the platen are arranged on opposite sides of an opening 30 through which the periphery of a knurled roller 14 is visible. The roller is firmly secured to a rotatable shaft 13 which is provided with an actuating crank 15 at its outer end. At the rear corners of the platen sleeves 16 are integrally formed in which parallel bores are provided. These bores have slidably mounted therein adjustable rods 17 which are connected at one end by a spacer strap 18. Said rods are secured in any adjusted position by thumb screws 19. The surface of the platen is provided with linear graduations 20 along its opposing marginal edges which are cooperated with by the strap when setting and alighting the latter.

Between the sleeves at the same end of the platen an upright hollow arm 21 extends. The chamber 22 in this hollow arm houses the mechanism for actuating a spindle which will be more fully hereinafter described.

This right angled arm 21 is provided with a

roof member 23 from which a lug 24 extends downwardly. The lug has pivotally attached thereto on a pin 25, pressure bar 26. The pressure bar is provided with a longer and shorter end. The shorter end of the pressure bar has a coil spring 27 secured thereto. Said spring extends diagonally downward and is directly attached to the lower portion of the arm of the device.

Enlargements 28 and 29 are formed on the outer extremity of the arm and are spaced apart from each other. These enlargements have aligned square openings therein which slidably receive a square spindle 30. The lower end of the square spindle 30 projects beneath the enlargement 29 and is bifurcated so that a cutting disk 31 may be anchored between the bifurcations upon a pin 32 which is secured in place by cotter pins or the like. The enlargements 28 and 29 serve as anchoring members upon which the ends of a toothed rack bar 33 is secured. The pressure lever 26 extends outwardly beyond the toothed rack bar between the enlargements 28 and 29 and adjacent to the rack bar. The teeth 34 of the rack bar are engaged by the lip 35 of a pivoted trigger 36 which is fulcrumed at 37. The longer end of the pressure lever is deformed into a right angled extension 38 which serves as a guard for the operator of the device. The trigger 36 has an offset finger plate 39 thereon which is contacted with when the trigger is manipulated. The longer end of the trigger is normally urged into raised position by a coil spring 40 which latter is housed in a cup 41 forming an integral part of the pressure lever.

A bell crank is pivotally mounted on a pin 42 on the pressure lever. This bell crank is an obtuse angled member comprising a long arm 43 and a short arm 44. The short arm 44 is slotted horizontally as indicated by the numeral 45 and this slot receives a pin 46 which latter is finally anchored on and projects from the side of the square spindle 30. The longer arm 43 of the bell crank describes a radial arc in passing through its movement and its outer end is adapted to project through an aperture 47 located in the bottom 48 of the arm 21 when said spindle has been lowered. The

short arm 44 of the bell crank is adapted to be normally lowered when a coil spring 49 is tensed by the lowering of the pressure lever.

The device is adapted to serve as a tile cutting machine or for other similar ceramics in either glazed or plain finish. The tile is placed upon a knurled roller 14 and rolled across the platen 10 beneath the cutting disk 31 by rotation of the crank 15. When a tile 10 has been placed upon the roller beneath the cutting disk, the pressure lever 26 is lowered by manipulating the extension 38. This pressure lever will carry with it in its arcuate swing the bell crank comprising the short and 15 long arms 44 and 43 and the trigger 36. The trigger will trip over the tips of the rack teeth 34 of the rack bar 33 and will engage the tooth at which downward pressure on the pressure bar 26 is released. As this downward swing 20 of the pressure bar occurs the bell crank being in engagement with the spindle 30 through the medium of the pin 46 will lower this spindle and when resistance against any additional downward movement of the spindle is 25 had as the cutting disk contacts with the surface of the tile, the bell crank will then be caused to rotate in a counter-clockwise direction while the pressure bar 26 is being lowered and when the arm 44 of this obtuse angled 30 bell crank rotates in a counter-clockwise direction the longer arm 43 being integral with the shorter arm will rotate with the latter and will tense the coil spring 49. This coil spring when tensed will augment or increase the tension 35 of the pressure lever upon the tile surface and will consequently cause the disk to bite deeper into the tile and as the latter is rolled across the path of the cutting disk 31 the same is divided or sheared.

40 It is to be noted that certain changes in form and construction may be made without changing the scope or spirit of the invention.

I claim:

1. In a tile cutting machine, a spindle, 45 means on said spindle for cutting a tile, means for adjusting the position of said tile, means for lowering said spindle to cutting position, and means for exerting a continuous downward pressure on said spindle.

50 2. In a tile cutting machine, a slideable non-rotatable spindle, means on said spindle for cutting a tile, means for conveying a tile under said spindle, slideable means for adjusting the position of a tile, a spindle lowering bar, 55 releasable means for locking said bar in lowered position, and means on said bar engaging said spindle for exerting a continuous downward pressure on said spindle.

60 3. In a tile cutting machine, a platen, a right angled arm thereon, a spindle slideable in said arm, a cutting disk on said arm, rods, sleeves on said platen receiving said rods, means secured to said rods for adjusting the position of a tile, means for conveying a tile under said cutting disk, a pivoted spindle

lowering bar, releasable means for locking said bar in lowered position, and means on said bar engaging said spindle for exerting a continuous downward pressure on said spindle.

70 4. In a tile cutting machine, a support platen, a right angled arm thereon, a spindle movable vertically in said arm, a cutting disk on said arm, sleeves on said platen, rods slideable in said sleeves, a strap rigid with one end of said rods spanning said platen, graduated scales on said platen cooperating with said strap, means for conveying a tile under said cutting disk, a pivoted spindle lowering bar, 75 releasable means for locking said bar in lowered position, and means on said bar engaging said spindle for exerting a continuous downward pressure on said spindle.

75 5. In a tile cutting machine, a support platen, a right angled arm thereon, a spindle movable vertically in said arm, a cutting disk on said arm, means for adjusting the position of a tile beneath said cutting disk, a roller rotatably mounted in said platen, the periphery of said roller being raised above the surface of said platen, a crank adapted to rotate said roller to convey tile across said platen, a spindle lowering bar independent of said spindle, releasable means for locking said bar in lowered position and means on said bar engaging said spindle for exerting a continuous downward pressure on said spindle.

80 6. In a tile cutting machine, a support platen, a right angled arm thereon, a spindle movable vertically in said arm, a cutting disk on said arm, means for adjusting the position of a tile beneath said cutting disk, a roller rotatably mounted in said platen, the periphery of said roller being raised above the surface of said platen, a crank adapted to rotate said roller to convey tile across said platen, a spindle lowering bar independent of said spindle, 85 releasable means for locking said bar in lowered position and means on said bar engaging said spindle for exerting a continuous downward pressure on said spindle.

85 7. In a tile cutting machine, a support platen, a right angled arm thereon, a spindle movable vertically in said arm, a cutting disk on said arm, means for adjusting the position of a tile beneath said cutting disk, a roller rotatably mounted in said platen, the periphery of said roller being raised above the surface of said platen, a crank adapted to rotate said roller to convey tile across said platen, a spindle lowering bar independent of said spindle, 90 a rack on said arm and means on said bar engaging said rack for releasably locking said bar in lowered position, and means on said bar engaging said spindle for

exerting a continuous downward pressure on said spindle, and means mounted on said bar engaging said spindle for causing said spindle to move with said bar when said bar is lowered.

8. In a tile cutting machine, a support platen, a right angled arm thereon, a spindle movable vertically in said arm, a cutting disk on said arm, means for adjusting the position of a tile beneath said cutting disk, a roller rotatably mounted in said platen, the periphery of said roller being raised above the surface of said platen, a crank adapted to rotate said roller to convey tile across said platen, a spindle lowering bar independent of said spindle, a rack on said arm and a trigger pivoted on said bar engageably with said rack for retaining said bar in lowered position, and means on said bar engaging said spindle for exerting a continuous downward pressure on said spindle, and means mounted on said bar engaging said spindle for causing said spindle to move with said bar when said bar is lowered.

25 9. In a tile cutting machine, a support platen, a right angled arm thereon, a spindle movable vertically in said arm, a cutting disk on said arm, means for adjusting the position of a tile beneath said cutting disk, a roller rotatably mounted in said platen, the periphery of said roller being raised above the surface of said platen, a crank adapted to rotate said roller to convey tile across said platen, a spindle lowering bar independent of said spindle, a rack on said arm and a trigger pivoted on said bar engageably with said rack for retaining said bar in lowered position, and means on said bar engaging said spindle for exerting a continuous downward pressure on said spindle, a bell crank pivoted on said bar, and means for causing engagement of said bell crank with said spindle.

10. In a tile cutting machine, a support platen, a right angled arm thereon, a spindle movable vertically in said arm, a cutting disk on said arm, means for adjusting the position of a tile beneath said cutting disk, a roller rotatably mounted in said platen, the periphery of said roller being raised above the surface of said platen, a crank adapted to rotate said roller to convey tile across said platen, a spindle lowering bar independent of said spindle, a rack on said arm and a trigger pivoted on said bar engageably with said rack for retaining said bar in lowered position, and means on said bar engaging said spindle for exerting a continuous downward pressure on said spindle, a bell crank pivoted on said bar, said bell crank having a slotted end and means on said spindle engaged in said slotted end of said bell crank for rotating said bell crank when said spindle is lowered.

65 11. In a tile cutting machine, a support

platen, a right angled arm thereon, a spindle movable vertically in said arm, a cutting disk on said arm, means for adjusting the position of a tile beneath said cutting disk, a roller rotatably mounted in said platen, the periphery of said roller being raised above the surface of said platen, a crank adapted to rotate said roller to convey tile across said platen, a spindle lowering bar independent of said spindle, a rack on said arm and a trigger pivoted on said bar engageably with said rack for retaining said bar in lowered position, and means on said bar engaging said spindle for exerting a continuous downward pressure on said spindle, a bell crank pivoted on said bar, said bell crank having a slotted end, a pin on said spindle registering in the slotted end of said bell crank and means connected to said bell crank for causing said spindle to exert a continuous pressure on a tile when said spindle is lowered by said bar.

12. In a tile cutting machine, a support platen, a right angled arm thereon, a spindle movable vertically in said arm, a cutting disk on said arm, means for adjusting the position of a tile beneath said cutting disk, a roller rotatably mounted in said platen, the periphery of said roller being raised above the surface of said platen, a crank adapted to rotate said roller to convey tile across said platen, a spindle lowering bar independent of said spindle, a rack on said arm and a trigger pivoted on said bar engageably with said rack for retaining said bar in lowered position, and means on said bar engaging said spindle, a bell crank pivoted on said bar, said bell crank having a slotted end, a pin on said spindle registering in the slotted end of said bell crank and a coil spring secured to said bell crank for causing said spindle to be urged downwardly when said bar lowers said spindle.

In testimony whereof I affix my signature.
ERNEST H. WOLBER.
